UNITED STATES PATENT OFFICE.

IRA A. WEAVER, OF SPRINGFIELD, ILLINOIS.

CHUCK.

No. 893,958.

Specification of Letters Patent.

Patented July 21, 1908.

Application filed June 15, 1904. Serial No. 212,741.

To all whom it may concern:

Be it known that I, IRA A. WEAVER, a citizen of the United States, residing at Springfield, in the county of Sangamon and State of Illinois, have invented certain new and useful Improvements in Chucks, of which the following is a specification.

This invention relates to chucks and more particularly to chucks adapted to hold drills, 10 reamers, taps, and the like, and has among its salient objects, to provide a chuck capable of receiving and firmly holding tools of the character referred to which have round shanks, thus saving the added expense of 15 providing tools with tapering or specially formed shanks; to provide a chuck to which it is possible to attach a tool and lock it in operative position during full speed of the machine, or from which it is possible to re- 20 move such tool without in any way interfering with or stopping the movement of the machine, making it possible to instantly remove a drill or the like and substitute another of different size; or in tapping holes, 25 the tap can be run through the work, released and allowed to drop out of the chuck and afterwards instantly replaced without interfering with a continuous and uniform operation of the machine; to provide a chuck 30 of the character referred to adapted to receive tools with shanks of various sizes and to automatically center the tool as it is inserted and locked in the chuck; to provide a chuck with gripping jaws in the form of 35 rollers; and in general, to provide a practicable, durable and efficient chuck of the character referred to.

To the above ends the invention consists in the matters hereinafter described and more 40 particularly pointed out in the appended claims.

The invention will be readily understood from the following description, reference being had to the accompanying drawings, in 45 which

Figure 1 is an elevation of the chuck, showing a drill in fragment attached thereto; Fig. 2 is a top plan view with the chuck shank removed; Fig. 3 is a sectional view 50 taken on line 3—3, of Fig. 1; Fig. 4 is a sectional view taken on line 4—4, of Fig. 1; Fig. 5 is a sectional view taken on line 5—5, of Fig. 1; Fig. 6 is a vertical sectional view of the chuck with shank broken off to reduce 55 the size of the figure; Fig. 7 is an elevation of the body of the chuck with all parts re-

moved; Fig. 8 is a vertical sectional view of the body of the chuck; Fig. 9 is an elevation of the roller cage; Fig. 10 is a cross sectional view of said cage on line 10—10 of Fig. 9; 60 Figs. 11 and 12 are detail views of the locking band; Figs. 13 and 14 are detail views of the releasing band; Fig. 15 is an elevation of a spring for releasing band.

Referring to the drawings, 1 designates a 65 chuck body comprising a hollow cylindrical shell of uniform exterior diameter as to its lower portion and of slightly reduced exterior diameter as to its upper portion.

2 designates a taper shank for attaching 70 the chuck to the machine and as different machines require shanks of different taper, it is preferably made detachable from the chuck body by a taper driving fit, as indicated in Fig. 6, although it may be secured in any 75 desirable manner, as by screwing it thereto, or making it integral therewith.

The chuck body 1 is provided on its interior with a plurality of curved, eccentrically disposed cam faces 3, preferably made 80 rough by fluting or nurling, and each terminating at one side in a more or less abruptly inturned portion forming seats 4, hereinafter referred to.

5 designates a circumferentially extending 85 slot through the wall of the chuck body and opening into the interior thereof at a point adjacent the end termination of said cam faces.

6 designates a circumferentially extending 90 cam groove or channel cut into the exterior wall of said body just above the slot 5, and somewhat shorter; while 7 designates a similar groove at the upper edge of the chuck body immediately above and somewhat 95 shorter than the groove 6, said cam grooves being made shallow toward one end until they merge into the outer surface of the chuck body, as indicated by Figs. 2, 3 and 7.

8 designates a cage for gripping rolls hereinafter referred to, said cage being mounted within the chuck body 1 and provided at its upper end with a spindle 9 seated in a bearing 10 in the lower end of the shank 2 (see Fig. 6). The lower end of said cage is provided with a washer-like base 11, while through the side walls thereof are longitudinally extending slots 12 provided at each end with transversely extending roll seats 13—14 within which are seated gripping rolls 15, 110 preferably provided with fluted or knurled surfaces. The diameter of said rolls is some-

what greater than the thickness of said cage wall so that their peripheries project slightly beyond said wall into bearing with the cam faces 3, said rolls being adapted to be moved inwardly by the action of said cam faces, in the manner and for the purpose hereinafter described.

16 designates a coiled spring mounted around the spindle 9 upon said cage and connected at one end with a pin 17 on the inner end of the shank 2 and at the other end to a pin 18 upon said cage, said spring operating to hold said cage yieldingly in inoperative position with the rolls resting in the seats 4 of the cam faces 3, as indicated in Fig. 5. The cage 8 is provided at its lower end with a central opening 8' adapted to receive the shank of the tool A, and to this end the rolls 15 are pointed at their lower ends to facilitate the entrance of the tool shank into the center of the cage.

In the upper portion of the cage body is a transversely extending wedge-shaped hole 19 arranged to register with the slot 5 in the body of the chuck. Into this hole is fitted a key 20 provided with a spring lip 20', the outer ends of said key and spring projecting and moving within the slot 5, in the manner indicated in Fig. 4.

21 designates a sleeve or band provided on its exterior with a knurled surface and on its interior with two projecting lugs 22-23, said band fitting upon the exterior of said chuck body and so positioned that the lugs 22-23 rest on opposite sides of the end of the key 20 and the spring lip 20', there being provided notches 24 (see Fig. 7) in the body of the chuck to allow the sleeve to be placed upon said body. It will be obvious from the foregoing that if said locking sleeve 21 is grasped by the hand of the operator during the revolution of the chuck body, it will operate to stop the rotation of the roll cage within the chuck body, causing the cam faces 45 of the chuck body to act upon and move the gripping rolls 15 uniformly and simultaneously toward the axis of the cage, which is concentric with the chuck body, and into gripping engagement with the shank of the tool inserted therein. The spring lip 20' against which the holding force is applied through the lug 22, is strong enough to overcome the tension of the coiled spring 16 which tends all the while to move the cage 55 and the rolls contained therein forwardly into open or inoperative position. This construction and arrangement is such that the rolls are held in gripping engagement with the tool shank under spring pressure. In other words, the locking sleeve 21 which holds the cage and the rollers in the gripping position, engages said cage by means of the lug 22 pressing against the spring lip 20' mounted upon the key 20 which extends 60 through said cage. When the locking sleeve

is moved relatively to the chuck body and locked in a given position, in a manner hereinafter referred to, it moves said cage with it and holds it by means of the engagement between the lug 22 and the spring lip 20', the tension of the spring lip tending all the while to move the key 20 and the cage 8 into the gripping position. Upon releasing the locking means, to be described, the spring 16 upon the cage, the tension of which has been increased by the relative movement of the cage within the chuck body, moves said cage, together with the key 20 and sleeve 21, back to the normal or open position. The cam faces, being symmetrically arranged and of a uniform curvature, operate to automatically center the tool within the chuck as it is locked into operative position. In order to automatically lock said locking band and prevent its forward movement when released and the consequent release of the gripping members, a locking roll 25 is placed movably within the circumferentially extending channel 6 between the body of the chuck and the interior wall of the locking band 21, whereupon as soon as the locking band starts forward with the moving chuck after being released by the operator, the locking roll 25 wedges between said band and the chuck body with a binding effect, thus preventing the locking band from moving forward under the tension of the coiled spring 16 and releasing the gripping members.

A releasing band 26 is provided, having a knurled outer surface corresponding to that of the locking band 21 and having on its interior a lug 27 adapted to move in the groove 7 in the upper part of the chuck body. Said lug is provided with a pair of downwardly projecting arms 28-28 which rest on opposite sides of the locking roll 25 within the locking band 21. When it is desired to release the locking band and the gripping members, the operator grasps the releasing band on the revolving chuck body which operates to carry the locking roll 25 out of its binding engagement between the band 21 and the chuck body and allows the locking band, the key 20 and the cage 8 to be thrown forward under the tension of the spring 16 and thereby release the gripping members.

In order to effect an immediate locking by the locking roll, a spring 29 is mounted in the groove 7 with its arms pressed against the end wall thereof and the lug 27, thereby holding the roll in such a position that it locks immediately upon any forward movement of the locking band and thus prevents the locking band from moving forward sufficiently to loosen the gripping members.

A confining ring or collar 30 is mounted upon the upper end of the chuck body to prevent the accidental removal of the releasing and locking bands. This confining ring may be secured in place in any desirable man-

ner. In the present instance it is provided with a notch 31 to receive the stud 32, after which it is turned sufficiently to bring the notch out of register with the stud.

5 The operation of the above described device will no doubt be readily understood from the above description, but may be briefly restated as follows: Assuming that the chuck is mounted in a machine adapted 10 for drilling holes and it is desired to insert a drill or other tool, the operator takes the tool in one hand and inserts it into the central opening of the chuck body in the usual manner and with the other hand he grasps the 15 locking band 21. This operates to stop the cage and the locking rolls and causes the cam faces to move the gripping members inwardly into gripping engagement with the shank of the tool. As the operator releases 20 his hold upon the locking band, it starts forward under the tension of the coiled spring, whereupon it is locked against forward movement by the binding of the roll 25 between the band and the chuck body. If the operator 25 desires to release the drill to substitute another without stopping the machine, he simply grasps the releasing band 26 the stopping of which operates to carry the locking roll 25 out of binding engagement and allows 30 the locking band to be carried forward under the tension of the spring 16. Should this band stick for any reason, the lug 23 engaging the rear side of the key 20 enables the operator to manually turn it forward.

35 While I have shown a single embodiment of my invention, I wish it to be understood that the principle thereof may be embodied in widely varying structures. For example, I have illustrated and prefer to employ a series of cylindrical rolls constituting the gripping members of the chuck because such rolls are readily mounted, easily kept in place and afford a long bearing on the tool shank, but it will be understood that instead of cylindrical rolls, tapered rolls might be employed where the tool stock or shank is tapered. Furthermore a series of balls might be substituted for the rolls affording the like wedging action and the long bearing, the cage being adapted to hold such balls.

I claim:

1. In a chuck, the combination of a rotatable driving chuck body having internal cam tracks, gripping rollers coöperating 55 with said tracks, a cage spacing said rollers apart and housed within said chuck body, and means to turn said cage relatively to said body to throw said rollers into and out of tool gripping action, substantially as described.

2. In a chuck, the combination of a hollow body provided with means adapting it to be secured to a spindle or other holder, jaws within said body, a spacing cage for the jaws 60 relatively to the body, coöperating

means between the jaws and the body adapted to move the jaws radially upon relative rotation of the cage and body, and means extending to the exterior of the body whereby the cage may be rotated to permit 70 the release of the jaws, substantially as described.

3. In a chuck, the combination of members adapted to grip and release a tool or similar article, a chuck body having means 75 to force said members into tool gripping position and to permit them to release a tool, a cage to space said members apart, means acting to move said cage and body relative to one another to permit said members to 80 release the tool, and means to lock said cage with the members in tool gripping position, substantially as described.

4. In a chuck, the combination of rollers adapted to grip and release a tool or similar 85 article, a chuck body having cam tracks co-operating with said rollers to force them into tool gripping position and to permit them to release a tool, a cage to space said rollers apart, spring means to move said cage and 90 body relative to one another to permit said rollers to release a tool, and means to lock said cage with the rollers in tool gripping position, substantially as described.

5. In a chuck, the combination of tool 95 gripping members, a chuck body having means to coöperate with said members to cause them to grip or permit them to release a tool or similar article, a cage for said members movable relative to said chuck 100 body, manually actuated means to move said cage whereby said members are caused to grip a tool, automatic means to move said cage to permit said members to release a tool, and means to lock said cage with the 105 members in tool gripping position, substantially as described.

6. In a chuck, the combination of members adapted to grip and to release a tool or similar article, a chuck body having means 110 to force said members into tool gripping position and to permit them to release a tool, a cage for said members, manually actuated means to move said cage relative to said body whereby said chuck body means 115 are caused to operate said members, a spring connection between said manually actuated means and said cage whereby the latter is spring pressed to position to maintain said members in gripping relation, and means to lock said manually-actuated means in position, substantially as described.

7. In a chuck, the combination of members adapted to grip and to release a tool or similar article, a chuck body having means 125 to force said members into tool gripping position and to permit them to release a tool, a cage for said members, manually actuated means to move said cage relative to said body whereby said chuck body means 130

are caused to operate said members, a spring connection between said manually actuated means and said cage whereby the latter is spring pressed into position to maintain said members in gripping relation, a positive connection between said manually actuated means and said cage whereby the latter may be moved to such a position that the gripping members are released from the tool, and means to lock said manually-actuated means in position, substantially as described.

8. In a chuck body, the combination of members adapted to grip and to release a tool, a chuck body having means to force said members into tool gripping position and to permit them to release a tool, a cage for said members, a bar or key secured to said cage, a spring fastened to said cage, a manually actuated means to move said cage relative to said body whereby said chuck body means are caused to operate said members, said manually actuated means having projections engaging said bar or key and said spring, and means to lock said manually-actuated means in position to retain said members in tool gripping relation, substantially as described.

9. In a chuck, the combination of members adapted to grip and to release a tool or similar article, a chuck body having means to force said members into tool gripping position and to permit them to release a tool, a cage for said members, and a sleeve rotatably mounted on said chuck body connected to said cage and adapted to move the latter relative to said body whereby said chuck body means are caused to operate said members, substantially as described.

10. In a chuck, the combination of rollers adapted to grip and to release a tool or similar article, a rotatable chuck body having cam tracks coöoperating with said rollers and adapted to force them into tool gripping position and to permit them to release a tool, a cage for said rollers rotatably mounted in said chuck body, a sleeve rotatably mounted on said body, and means connecting said sleeve with said cage whereby the latter may be turned relative to said body by said sleeve, thereby causing said rollers to travel on said cam tracks, substantially as described.

11. In a chuck, the combination of a body provided with a plurality of longitudinally disposed gripping rollers arranged to form a socket for the reception of a tool shank, means for bringing said rollers into frictional engagement with said shank, and means for locking the rollers in their gripping position, substantially as described.

12. In a chuck, the combination of members adapted to grip and to release a tool or similar article, a chuck body having means to force said members into tool gripping position and to permit them to release a tool, a cage for said members movable relatively to

said chuck body, and means to lock said cage with the members in tool gripping position, substantially as described.

13. In a chuck, the combination of members adapted to grip and to release a tool or similar article, a chuck body having means to force said members into tool gripping position and to permit them to release a tool, a cage for said members movable relatively to said chuck body, and a frictional lock to hold said cage in such position that the members grip the shank of the tool, substantially as described.

14. In a chuck, the combination of members adapted to grip and to release a tool or similar article, a chuck body having means to force said members into tool gripping position and to permit them to release a tool, said chuck body having a wedge surface, a cage for said members movable relatively to said chuck body, means for moving said cage, and a friction lock coöperating with said last mentioned means and said wedge surface to lock said members in tool gripping position, substantially as described.

15. In a chuck, the combination of members adapted to grip and to release a tool or similar article, a chuck body having means to force said members into tool gripping position and to permit them to release a tool, a cage for said members movable relatively to said chuck body, a sleeve to operate said cage, a lock coöperating with said sleeve to maintain said members in gripping position, and a releasing sleeve to unlock said members, substantially as described.

16. In a chuck, the combination of rollers adapted to grip and to release a tool or similar article, a rotatable chuck body having cam tracks to force said rollers into tool gripping position and to permit them to release a tool, a cage for said members movable relatively to said chuck body, a cage operating sleeve rotatably mounted on said body, means to lock said sleeve with said rollers in gripping position, and a releasing sleeve rotatably mounted on said body adapted to unlock said cage operating sleeve, substantially as described.

17. In a chuck, the combination of members adapted to grip and to release a tool or similar article, a chuck body having means to force said members into tool gripping position and to permit them to release a tool and a wedge surface, a cage for said members movable relatively to said chuck body, means to move said cage, a locking roll coöperating with said cage moving means and with said wedge surfaces, to lock said cage with said members in gripping position, and means to unlock said cage, substantially as described.

18. In a chuck, the combination of rollers adapted to grip and to release a tool or similar article, a rotatable chuck body having

internal cam tracks adapted to coöperate with said rollers to force them into tool gripping position and to permit them to release a tool, said chuck body also having a wedge 5 surface, a cage for said rollers rotatably mounted in said chuck body, a cage operating sleeve rotatable on said body, a locking roll coöoperating with said sleeve and with said wedge surface to lock said cage with its 10 rollers in gripping position, a releasing sleeve rotatable on said body and having projections coöoperating with said locking roll to unlock said cage, substantially as described.

19. In a chuck, the combination of a chuck 15 body having cam tracks, rollers adapted to co-act with said cam tracks and grip and release a tool shank, means to move said rollers relatively to said tracks whereby to cause them to grasp a tool shank including a 20 sleeve rotatable on said body, and a second sleeve connected with said rollers, rotatable on said body, and adapted to cause said rollers to release the tool shank, substantially as described.

25 20. In a chuck, the combination of members adapted to grip and release a tool or similar article, a chuck body having means to force said members into tool gripping position and to permit them to release a tool,

a cage for said members, manually-actuated 30 means to move said cage relatively to said body whereby said chuck body means are caused to operate said members, a spring connection between said manually-actuated means and said cage whereby the latter is 35 spring-pressed to position to maintain said members in gripping relation, means to lock said manually-actuated means in position, and a spring acting on said cage tending to move the same to throw said gripping members out of tool gripping action, substantially as described.

21. In a chuck, the combination of a plurality of tool gripping members, a cage for spacing said members apart, a chuck body 45 having means for causing said members to grip a tool, said cage being housed within and rotatable relatively to said chuck body, and a bar or rod located in apertures or recesses in said chuck body and cage and acting to retain the cage in the body and limit the rotary travel thereof, substantially as described.
